United States Patent Office

Des. 216,558
Patented Feb. 10, 1970

216,558

PLATE OR SIMILAR ARTICLE

Ryotaro Takeoka, 221 Kitayamoto-cho, Nishikasugai-gun,
Aichi-ken, Japan

Filed Mar. 17, 1969, Ser. No. 16,287

Term of patent 3½ years

Int. Cl. D7—01

U.S. Cl. D44—15

The figure is a plan view of a plate or similar article showing my new design, a portion of the design being shown between dot and dash lines and a repeat portion being shown between dotted lines.

The plate is of a conventional configuration when viewed from the side and bottom thereof.

I claim:

The ornamental design for a plate or similar article, substantially as shown and described.
